UNITED STATES PATENT OFFICE

2,564,936

EMULSION SEPARATOR

John C. Vanden Berg, Fort Wayne, Ind., assignor
to Waste Conditioning Inc., Indianapolis, Ind.,
a corporation

Application March 24, 1948, Serial No. 16,777

3 Claims. (Cl. 252—362)

1

This invention relates to an emulsion separator. In the renovation and/or cleaning of journal box waste for example hot oil is frequently used to melt the ice, soften grease and remove moisture from the said waste subject to reclamation.

Heretofore one of the chief objections to the use of hot oil for such purpose has been that the oil and moisture removed from used journal box packing is already in a partially emulsified state, and this condition is aggravated by the use of a centrifugal extractor in separating the used oil and its moisture content from the used waste, either while running a break-down preparatory to the washing operation, or during an operation if the washing is effected by use of a centrifugal extractor.

Separation of such a resulting liquid heretofore could not be effected rapidly and economically. The chief object of the present invention therefor is to rapidly and economically effect such separation.

The chief feature of the present invention is to drive off the moisture as a vapor from the emulsion by causing thin films thereof to be subjected to high heat.

Other objects and features of the invention will be set forth more fully hereinafter.

The full nature of the invention will be understood from the accompanying drawings and the following description and claims:

In the drawings Fig. 1 is a transverse sectional view through an emulsion separating apparatus embodying one form of the invention.

Fig. 2 is a top plan view thereof.

Fig. 3 is a longitudinal sectional view taken on line 3—3 of Fig. 1 of the drawings and in the direction of the arrows.

In the drawings 10 indicates a pair of base brackets to which is secured the cross member in the form of reversed angles 11. Supported by the same is a tank 12 see Fig. 1. Preferably but not necessarily, same has a bottom intake 13 for reception of the emulsion. Vertically disposed in said vertically disposed tank is a heating unit 14. Same may comprise parallel or series connected steam coils, or electrically operated heating rods, preferably connected in parallel.

Near the top of tank 12 is a full width discharge 15 and a transfer trough 16 which provides gravity flow to a downwardly directed full width channel 17, same at the bottom having full width communication with the bottom of vertical tank 18 at 19. Disposed in tank 18 is a heating structure 20 similar to heating structure 14 in tank 12.

Tank 18 at its upper end and substantially coextensive with the length thereof has overflow

2

opening or outlet 21. A trough 22 discharges to a hopper like chamber 23 having overflow outlet 24. The trough has a bottom 25 with discharge holes 26 that in turn discharges to a vertical series of heating coils 28. Therebeneath is collection device 27 having a suitable discharge 27a.

The heating structure 28 is similar to structures 14 and 20. These may be connected in parallel or series or series-parallel relation and 10 may have the same or different operating temperatures as desired or required.

Over all of these tanks and/or heating columns there may be disposed a vacuum subjected canopy, hood or cover 39. Thus when the emulsion relation is broken down and moisture is freed 15 it is vaporized and then is drawn off through the cover 39 see Fig. 1. The water-freed oil is collected at 27 and drawn or drained off at 27a as desired or required and subjected to further purification.

The present apparatus, therefore, provides an efficient, continuous operable separator for the separation of a water-oil emulsion and removal of the water when so separated.

25 While, herein but two successive tanks 12 and 18 are illustrated, each having a heater and structure therein and in effect a third open channel over coils 28 and the flow is from one end to the other thereover, the number of stages may be 30 increased at will. Also while the flow in all but the last stage is upward, flow in said stages may be reversed and drawoff to the last stage will be from the bottom of the next succeeding stage device and discharge to the hopper 23.

35 The effectiveness of the present apparatus resides in the flowing of a thin film of an emulsion at the desired temperature over successive heater structures so that the additional heat will break down the emulsion phase or state thereby releasing the moisture and gases and the vaporizing of the moisture so that said vapor and the freed gases may escape or be drawn off as desired.

While the apparatus has been described as of the heat cycle addition type, whenever desired or 45 required the structures 14, 20 and/or 28 may be of the refrigerating type for certain refrigerated separable emulsions.

Such emulsions need not necessarily be of oil and water but may be of other character just so 50 long as the emulsion is temperature change separable into its components.

While the invention has been illustrated and described in great detail in the drawings and foregoing description, the same is to be considered as 55 illustrative and not restrictive in character.

The several modifications described herein as

well as others which will readily suggest themselves to persons skilled in this art, all are considered to be within the broad scope of the invention. Reference being had to the appended claims.

The invention claimed is:

1. A demulsifier comprising a plurality of vertically disposed tanks including an intake tank, an intermediate tank and a discharge tank, the intake tank having side walls relatively closely spaced to provide an elongated relatively narrow passage for the oil and upwardly therethrough and having an intake at its bottom, said tank being open at its top for overflow discharge, a plurality of heat exchange units disposed in vertically spaced relation in said tank, one above the other and occupying a substantial portion of the tank between the side walls thereof, a relatively narrow conduit coextensive with the length of said intake tank having a relatively narrow cross section, an intake at its top receiving the overflow from said intake tank and a discharge opening at its bottom, an intermediate tank of relatively narrow cross section communicating at its bottom with the discharge end of said conduit and having an overflow opening at its top, heat exchange elements disposed in vertical spaced relation one above the other in said intermediate tank, the discharge tank having a discharge opening at its lower end and an elongated receiving trough extending longitudinally thereof and receiving the overflow discharge from the top of said intermediate tank and provided with trickle openings in its bottom, vertically spaced heat exchange units disposed one above another in said discharge tank and in vertical alignment with the trickle discharge opening in said trough.

2. A demulsifier comprising a plurality of vertically disposed tanks including an intake tank, an intermediate tank and a discharge tank, the intake tank having side walls relatively closely spaced to provide an elongated relatively narrow passage for the oil and upwardly therethrough and having an intake at its bottom, said tank being open at its top for overflow discharge, a plurality of heat exchange units disposed in vertically spaced relation in said tank, one above the other and occupying a substantial portion of the tank between the side walls thereof, a relatively narrow conduit coextensive with the length of said intake tank having a relatively narrow cross section, an intake at its top receiving the overflow from said intake tank and a discharge opening at its bottom, an intermediate tank of relatively narrow cross section communicating at its bottom with the discharge end of said conduit and having an overflow opening at its top, heat exchange elements disposed in vertical spaced relation one above the other in said intermediate tank, the discharge tank having a discharge opening at its lower end

and an elongated receiving trough extending longitudinally thereof and receiving the overflow discharge from the top of said intermediate tank and provided with trickle openings in its bottom, vertically spaced heat exchange units disposed one above another in said discharge tank and in vertical alignment with the trickle discharge opening in said trough, and a single canopy covering the tops of all of said troughs.

3. A demulsifier comprising a plurality of vertically disposed tanks including an intake tank, an intermediate tank and a discharge tank, the intake tank having side walls relatively closely spaced to provide an elongated relatively narrow passage for the oil and upwardly therethrough and having an intake at its bottom, said tank being open at its top for overflow discharge, a plurality of heat exchange units disposed in vertically spaced relation in said tank, one above the other and occupying a substantial portion of the tank between the side walls thereof, a relatively narrow conduit coextensive with the length of said intake tank having a relatively narrow cross section, an intake at its top receiving the overflow from said intake tank and a discharge opening at its bottom, an intermediate tank of relatively narrow cross section communicating at its bottom with the discharge end of said conduit and having an overflow opening at its top, heat exchange elements disposed in vertical spaced relation one above the other in said intermediate tank, the discharge tank having a discharge opening at its lower end and an elongated receiving trough extending longitudinally thereof and receiving the overflow discharge from the top of said intermediate tank and provided with trickle openings in its bottom, vertically spaced heat exchange units disposed one above another in said discharge tank and in vertical alignment with the trickle discharge opening in said trough, and a collecting trough at the bottom of said discharge tank.
